UNITED STATES PATENT OFFICE

92,986

DESIGN FOR A BEVERAGE DISPENSER

Neil Conwell Stilwell, La Fayette, Ind.

Application May 3, 1934, Serial No. 51,677

Term of patent 7 years

To all whom it may concern:

Be it known that I, NEIL CONWELL STILWELL, a citizen of the United States, residing at La Fayette, in the county of Tippecanoe and State of Indiana, have invented a new, original, and ornamental Design for a Beverage Dispenser, of which the following is a specification, reference being had to the accompanying drawing, forming part thereof.

showing my new design, the side of the beverage dispenser opposite to that shown having substantially the same appearance as the side of the beverage dispenser appearing in the drawing.

Figure 2 is a top view of the same.

I claim:

The ornamental design for a beverage dispenser as shown and described.

NEIL CONWELL STILWELL.
